UNITED STATES PATENT OFFICE.

ISRAEL BERENSON, OF BOSTON, MASSACHUSETTS.

DESIGN FOR A TRAFFIC SIGNAL.

Application filed December 19, 1922. Serial No. 4,640. Term of patent 14 years.

To all whom it may concern:

Be it known that I, ISRAEL BERENSON, a citizen of the United States, residing at Boston, in the county of Suffolk and State of Massachusetts, have invented a new, original, and ornamental Design for Traffic Signals, of which the following is a specification, reference being had to the accompanying drawings forming a part thereof.

In the drawings:

Figure 1 is a plan view of a traffic signal showing my new design.

Fig. 2 is a front elevation of said traffic signal.

I claim:

The ornamental design for a traffic signal as shown.

In testimony whereof I have hereunto set my hand in presence of two subscribing witnesses.

ISRAEL BERENSON.
